FEEDWATER HEATER ARRANGEMENT FOR
STEAM TURBINE POWER PLANTSJack E. Downs, Schenectady, N. Y., assignor to
General Electric Company, a corporation of
New York

Application August 21, 1952, Serial No. 305,610

6 Claims. (Cl. 60—67)

1

This invention relates to elastic fluid turbine power plants, particularly to a compound turbine plant with a reheat between turbines, although it may also be used in connection with "non-reheat" turbines. The characteristic feature resides in a novel feedwater heater arrangement for such power plants.

As the cost of fuel has progressively increased, the manufacturers of large steam turbine power plants have made great efforts to take full advantage of every smallest possible gain in thermodynamic efficiency. This has led to a continuous trend towards ever larger power generating units, and, in recent years, increasing popularity of the so-called "reheat" type of compound turbine, in which the motive fluid passes through a high pressure turbine, then is reheated before entering subsequent lower pressure turbines. The present invention relates particularly to an improved feedwater heater arrangement for such a turbine.

The object of the present invention is to provide an improved feedwater heater arrangement, particularly adapted for a reheat type turbine, which effects a small but significant improvement in the overall thermal efficiency of the power plant.

Other objects and advantages will become apparent from the following description taken in connection with the accompanying drawing, in which the single figure represents diagrammatically a steam turbine power plant having a compound turbine with a reheat between the high pressure and low pressure turbine units and an improved multiple feedwater heater arrangement incorporating the invention.

Generally, the invention is practiced by providing at least two feedwater heaters in series between the boiler feed pump and the boiler, the first being heated by steam extracted from the high pressure turbine unit and the second having a special high temperature section arranged to extract a certain increment of thermal energy from the hotter steam extracted from the low pressure turbine. This heat increment is added to the feedwater discharged from the first heater, and serves at the same time to improve the thermal efficiency of the second heater by reducing the temperature differential between the steam and the feedwater being heated by it.

Referring now more particularly to the drawing, the power plant is represented diagrammatically as comprising a steam generator including a feedwater pump 1 supplying preheated water to a boiler 2, from which highly super-

2

heated steam flows through the high pressure turbine 3, a reheat 4, and a low pressure turbine 5. The compound turbine 3, 5 may of course be arranged in many ways, being represented here as having a common rotor shaft driving a suitable load such as the electrical generator 6.

The feedwater heater system comprises a primary heater shown at 7 and a secondary heater 8. Heater 8 is actually two separate heat exchangers in one, namely, a first section shown at 9 and a second section 10.

The piping circuit interconnecting these components is as follows.

15 The feedwater pump 1 receives condensate from the hotwell of a condenser (not shown) or other suitable source in the power plant through conduit 11. The feedwater pump discharges through conduit 12 to a set of heat exchange tubes 10a, only one of which is shown in the feedwater heater section 10. From heater 10, the liquid flows by way of conduit 13 to a set of tubes 7a in the primary heater 7. Conduit 14 connects the heat exchange tubes 7a with the inlet manifold 9a of the special feedwater heater section 9. The high temperature manifold 9c is connected by conduit 15 with the boiler 2. Conduit 16 admits motive fluid to the high pressure turbine 3. The crossover conduit 17 contains the reheat 4 and leads motive fluid from the exhaust of the high pressure turbine 3 to the inlet of the low pressure turbine 5. Exhaust steam leaves turbine 5 through an exhaust conduit 18, which may communicate with other still lower pressure turbines (not shown).

35 The primary feedwater heater 7 has a special "desuperheating" section 7b, which may be conveniently formed by a plurality of baffles 7c arranged to cause the superheated steam to take a serpentine course relative to the heat exchange tubes 7a, as indicated by the flow arrows in the drawing. The heating steam is admitted to the desuperheating section 7b by conduit 19, which may communicate with the exhaust end of the high pressure turbine 3, as shown in the drawing. It will, however, be appreciated by those skilled in the art that conduit 19 may also extract steam from some higher pressure point in turbine 3 intermediate the inlet conduit 16 and the exhaust conduit 17.

40 After losing at least a part of its superheat in the desuperheater section 7b, the steam flows through the lower part of feedwater heater 7 and gives up a further increment of heat to the comparatively cooler liquid entering the lower

horizontal legs of the tubes 1a. Spent heating fluid from the heater 7 is discharged by way of conduit 20. This spent heating fluid may be further used in other heat exchangers in the power plant (not shown), but it may also conveniently discharge into the high temperature end of the feedwater heater section 10, as shown in the drawing.

The secondary heater section 10 is heated by steam extracted from the low pressure turbine 5 by a conduit 21. In accordance with the invention, this superheated steam extracted from turbine 5 does not pass directly into the feedwater heater 10 but first gives up a certain portion of its thermal energy in the special desuperheating section 9. As indicated by the flow arrows in the drawing, this heating steam flows from the lower end of heat exchanger 9 into the left-hand end of the feedwater heater section 10, then takes a serpentine course over the tubes 10a defined by the baffles 10b. Spent heating fluid is drained by conduit 22. The remaining thermal energy in this condensate may be utilized in other parts of the power plant, or it may be returned by means of a pump 23 directly into the feedwater pump discharge conduit 12.

To render more clear the method of operation, the temperatures and pressures of the feedwater and extraction steam are indicated by legends on the drawing, in degrees Fahrenheit and pounds per square inch, respectively. It will be observed that the secondary feedwater heater section 10 increases the temperature of the feedwater from 330° F. to 370° F., while the primary heater 7 further raises the temperature to 455° F. The special desuperheater section 9 still further increases the feedwater temperature to 464° F.

Attention is particularly directed to the relation between the temperature of the heating steam entering the desuperheater section 9 through conduit 21 and that of the condensate entering the heater 10 through conduit 12. As will be appreciated by those familiar with the thermodynamic theory of such power plants, there is an inherent loss in thermodynamic efficiency in the heat transfer processes occurring in the feedwater heaters 7, 8, which loss increases as the temperature differential between the hotter fluid and the fluid being heated becomes larger. Thus, if the highly superheated extraction steam in conduit 21 were discharged directly into the heat exchanger 10, the temperature difference between the extraction steam in conduit 21 (at 830° F.) and the liquid in the heat exchange tubes 10a (at well below 400° F.) would involve a substantial inherent thermodynamic loss. On the other hand, with my arrangement, the extraction steam supplied by conduit 21 loses a substantial part of its thermal energy in the desuperheater section 9, and at a smaller temperature differential, so that the heating fluid supplied to exchanger 10 is at a substantially lower temperature (perhaps about 485° F.), more nearly of the same order of magnitude as the highest temperature of the liquid within the tubes 10a. Thus, the heat exchange process in heater 10 has a significantly smaller inherent thermodynamic loss.

The importance of this arrangement lies also in the fact that in reheat type turbines the overall "plant efficiency" is found to improve as the temperature of the feedwater supplied to the boiler increases for a given "reheat pressure." In other words, the aim of the power plant designer is to have the temperature of the feed water in

conduit 15 just as high as possible for a given pressure of the heating fluid extracted through conduit 19, which, in the case illustrated in the drawings, is at the same pressure as the steam at the entrance 17 to the reheater 4.

It will thus be apparent that the special heater section 9 increases the overall efficiency of the plant by performing the dual function of (1) effecting a further increase in the temperature of the feedwater supplied to the boiler, and (2) reducing the inherent thermodynamic loss in the feedwater heater 10 by making the temperature of the heating fluid more nearly of the same order of magnitude as that of the liquid being heated.

Analysis shows that this arrangement may be expected to effect an overall improvement in plant efficiency on the order of .13%. While this gain seems small, it is of substantial importance in a turbine power plant having an output on the order of 200,000 kw. for an improvement in station efficiency of this order of magnitude may result in a saving of perhaps 600 tons of coal per year. In view of the highly developed state of the modern turbine power plant, and the importance of reducing fuel costs by every possible means, such a saving is of substantial significance to the power plant operator.

While only one form of the invention has been described specifically herein, it will be obvious to those familiar with the art that many changes in arrangement and substitutions of equivalent structures may be made without departing from the invention. As indicated above, the steam extracted through conduit 19 may be derived from an intermediate point in the high pressure turbine 3, and the spent heating fluid from the primary exchanger 7 may be used in ways other than being discharged into the heat exchanger 10 as shown. It will also be understood that a power plant of this type would not ordinarily have only two or three feedwater heaters as described herein, but may have a substantial number of still lower temperature heat exchangers ahead of the feedwater pump 1. Also, it is not necessary that the special heat exchanger 9 be incorporated in the same casing as the secondary feedwater heater 10. Thermodynamically the arrangement would be substantially the same if the heater 9 were divorced structurally from the heater 10; but in many cases it may be more economical to build these two heaters in a common casing, as shown in the drawing. My improved feedwater heater arrangement may be found advantageous in multi-stage turbines other than those having reheat, in which case it is only necessary that the steam extracted from the turbine for heating the secondary feedwater heater be at a significantly higher temperature than the feedwater leaving the primary feedwater heater. In such an arrangement the benefits derived would be somewhat less than in a reheat turbine power plant, but might still be worth having.

Many other alterations and substitutions of equivalents will occur to those skilled in the art, and it is of course desired to cover by the appended claims all such changes as fall within the true spirit and scope of the invention.

What I claim as new and desire to secure by Letters Patent of the United States is:

1. In a steam turbine power plant having a steam generator including a feedwater pump and a boiler supplying motive fluid to a high pressure turbine, a reheat, and a low pressure turbine in series, the combination of a first high tem-

perature feedwater heater and a second lower temperature feedwater heater connected in series with the boiler feed pump, and a third feedwater heater connected in series between said first heater and the boiler, the first heater being heated by steam extracted from the high pressure turbine, the third heater being heated by steam extracted from the low pressure turbine, and the second heater being heated by steam discharged from the third heater.

2. A steam turbine power plant in accordance with claim 1 in which the first feedwater heater is connected to discharge used heating fluid into the second feedwater heater at a temperature substantially lower than that of the heating fluid supplied to the third heater and of the same order of magnitude as the temperature of the fluid discharged by the third heater into the second heater.

3. In a steam turbine power plant having a steam generator including a feedwater pump and a boiler supplying motive fluid to a high pressure turbine, a reheat, and a lower pressure turbine in series flow relation, the combination of a primary feedwater heater and a secondary feedwater heater connected in series between the feedwater pump and boiler, the primary heater being heated by steam extracted from the high pressure turbine, the secondary heater including a first section connected in series between the primary heater and the boiler and a second section connected in series between the feedwater pump and the primary heater, the secondary heater being connected to be heated by steam extracted from the lower pressure turbine and flowing through said first section of the secondary heater and then through the second section thereof.

4. In a turbine power plant having a steam generator including a feedwater pump and a boiler supplying motive fluid to a high pressure turbine, a reheat, and a low pressure turbine in series, the combination of a first feedwater heater heated by steam extracted from the high pressure turbine, a second feedwater heater connected in series between the boiler feed pump and said first heater, and a third feedwater heater connected in series between said first

heater and the boiler, first conduit means for supplying steam extracted from the low pressure turbine to heat said third feedwater heater, the third heater being connected to discharge heating fluid into said second heater, and second conduit means for supplying spent heating fluid from the first heater to the second heater at a temperature substantially below that of the heating fluid supplied to the third heater and of the same general order of magnitude as that of the spent heating fluid discharged from the third heater into the second heater.

5. In a steam turbine power plant having a steam generator including a feedwater pump and a boiler supplying motive fluid to a multi-stage turbine, the combination of a first high temperature feedwater heater and a second lower temperature feedwater heater connected in series with the boiler feed pump, and a third feedwater heater connected in series between said first heater and the boiler, the first heater being connected to be heated by steam extracted from a high pressure point in the turbine, the third heater being connected to be heated by steam extracted from a lower pressure point in the turbine, and the second heater being connected to be heated by fluid discharged from the third heater.

6. In a steam turbine power plant having a steam generator including a feedwater pump and a boiler supplying motive fluid to a multi-stage turbine, the combination of a primary feedwater heater and a secondary feedwater heater, the primary heater being connected to be heated by steam extracted from a high pressure point in the turbine, the secondary heater including a first section connected in series between the primary heater and the boiler and a second section connected in series between the feedwater pump and the primary heater, the secondary heater being connected to be heated by steam extracted from a lower pressure point in the turbine and flowing through said first section of the secondary heater and then through the second section thereof.
